UNITED STATES PATENT OFFICE.

JOHN KOROSCHETZ, OF CHICAGO, ILLINOIS.

CAR SEAL.

Application filed July 5, 1927. Serial No. 203,400.

My invention relates to improvements in car seals and has special relation to car seals of the ribbon type.

The object of my invention is to provide a seal of the character mentioned which will provide a more secure lock for the ends of the seal strap, in which the possibility of opening the head, in which the ends of the strap are locked by edge pressure will be effectively eliminated; in other words, it is my object to provide a construction of strap ends and head for receiving and locking the ends therein and whereby the ends of the strap, when once entered, cannot be released without such a complete distortion or destruction of the head as to absolutely prevent the restoration of the seal to a condition where it might be used to indicate that a car is still sealed.

20 A particular feature of my invention is the formation of the end receiving head convex in transverse cross-section, and whereby transverse pressure applied to the head will tend to close the side walls of the head more firmly upon the strap ends rather than tend to release the ends by spreading the sides apart as in the constructions now in common use.

25 A further object is to provide a construction of such formation as to be readily produced by automatic punch and die machinery to the end that the cost shall be reduced to such a low point as to ensure commercial success.

30 My invention will be more readily understood by reference to the accompanying drawings forming part of this specification and in which:—

35 Fig. 1, is a plan view of the device, the strap shown in full lines and the head shown in dotted lines;

40 Fig. 2, is a longitudinal sectional view of the strap on the line 2—2 of Fig. 1, the head shown in dotted lines;

45 Fig. 3, is a front elevation of the seal as it appears in use;

Fig. 4, is a rear elevation of the seal as it appears in use;

Fig. 5, is a central longitudinal section on the line 5—5 of Fig. 3; and

50 Fig. 6, is a cross-section on the line 6—6 of Figs. 4 and 5.

55 In said drawings 1 is a sheet metal strap made of relatively thin sheet metal and preferably made of strap metal of uniform width. Strap metal of such form is an article of commerce and in making my seal I prefer to use

such strap metal, merely cutting pieces of suitable length from a long strip of metal and performing the necessary operations upon these pieces to make them of the form desired. 60 Besides these pieces of strap metal my seal includes a head piece 2 which is preferably made of a single piece of metal drawn into tubular form from a flat piece of sheet metal somewhat thicker than the strap and formed 65 into a head for receiving the ends of the strap 1. The head 2 is closed except at one end where the two ends of the strap 1 enter. When the head 2 is finished, as shown in the drawings, it is in the form of a relatively flat 70 pocket-like member having an opening 3 at one end slightly wider than the strap 1 and of a size in the other direction to just admit the two thicknesses of the strap, as shown in Fig. 5, and not large enough to admit a third 75 thickness.

In making the seal the ends of the strap are first formed and then the head 2 is permanently secured upon one end of the strap, the other end being adapted to be inserted 80 into the head and locked against removal when the seal is made use of.

The end 4 of the strap is formed to be secured permanently in the head 2. For this purpose the extreme portion of the end 4 is 85 bent up at a right angle to the strip to form a shoulder-like part 5, and as shown in Fig. 5, the head 2, in the process of manufacture is formed around this bent up part, the front wall of the head being formed down in front 90 of the part 5, as shown at 7, to prevent the withdrawal of the end 4 from the head. As an added security the end 4 is provided with a perforation 8 next to the shoulder 5 and the wall 6 of the head is forced into this opening as by means of a center punch, as shown at 8, thus providing a second hold of the head 2 upon the end 4 of the strap. 95

The end 4 of the strap has its corners cut off, as shown at 9, and consequently the shoulder part 5 is not as wide as the strap, this is for the purpose of accommodating the end of the strap in the head 2, as the head in its process of manufacture has a more or less round bottom. 100

The opposite end 10 of the strap is provided with an opening 11 and this end is rounded, as shown at 12, and slightly tapered edgewise to facilitate its entrance into the mouth 3 of the head. To provide a shoulder to enter the opening 11 of the end 10, when this end is pushed into the head, and lock 110

this end in the head, the end 4 is provided with a struck up projection 12. This projection 12 is formed up, making a short transverse incision or cut at 13 in the end 4 of the strap and forming the metal of the strap up into V-shape at the side of the cut toward the body of the strap, thus forming a projection opposed to the bent up end 5 and spaced therefrom. The projection 12 is V-shaped transversely of the strap and it presents an inclined surface 14 toward the body of the strap. When the end 4 is secured in the head 2 the inclined surface 14 of the projection 12 is presented toward the opening or mouth 3 of the cap so that when the opposite or free end 10 of the strap is pushed into the cap this end will slide up this inclined face of the projection 12, thus forcing the end 10 away from the end 4 sufficient to let it snap over the projection 12 and engage the base or flat end 15 of the projection. The side wall 16 of the head 2 which is adjacent to the projection 12 is rounded up both transversely, as shown in Fig. 6, and longitudinally, as shown in Fig. 5, thus providing space to permit the end 10 of the strap to rise over the projection 12. The rounded down portion 17 of the wall 16 beyond the projection 12 forces the free end 10 of the strap down toward the end 4 as the end 10 is forced into the cap, thus ensuring its engagement with the projection 12 and preventing it being disengaged therefrom by any jarring or hitting of the head.

35 As an additional means of locking the two ends against removal from the head the rear wall 18 of the head and which is the side opposite to the side 16 is forced inwardly, as shown at 19, at a point opposite to the projection 12 and is forced into the opening produced in the body of the strip by the forming up of the projection 12. This formation, shown at 19, produces a shoulder on the wall 18 of the head 2 which engages the end 4 of the strap at the cut 13. Furthermore, this projection 19 extends up into the V-shaped projection 12 and is in position to engage the opposite end 10 of the strap in addition to the engagement of the strap by the projection 12. The end 10 of the strap is thus locked against removal by the wall of the head as well as by the projection 12.

To prevent the possibility of the user attempting to force the free end 10 of the strap into the head at the rear side of the end 4 of the strap, there is provided a rounded projection 20 on the end 4 at a suitable position on the strap 1 so that when the end 4 of the strap is secured in the head the projection will be located close enough to the mouth 3 of the head to prevent the end 10 entering the mouth 3 at the wrong side.

For the purpose of additional security against the possibility of working the end 10 out of the head after it has once been in-

serted, there is provided a weakened transverse line 21 across the end 10 of the strap at such a position that when the end 10 is inserted into the head far enough to engage the projection 12 the line or cut 21 will be coincident with the mouth 3 of the head. Any attempt to work the end 10 free of the head by manipulating the strap will cause the strap to break at the line 21 and the short end 10 thus broken off will extend just to the mouth 3 of the head. If this end extended further out than this it might be possible to push the broken end of the strap between the two ends 4 and 10 and give the seal the appearance of being unbroken, but such deceit is precluded by the arrangement described.

In making the cut 21 it is preferably made shorter in length than the width of the strap, as best shown in Fig. 1, so that the strap will have sufficient strength and rigidity at this point to be properly locked without fracture. Further the cut is preferably made by means of a tool pressed into the strap from the front, thus forcing the metal of the strap out toward the back of the strap, as shown at 22. This projected part or lip forms a shoulder so located that it contacts with the adjacent end of the head 2 when the end 10 of the strap is inserted far enough to engage the projection 12 and prevents any attempt to force the end 10 farther into the head.

The old form of head which is somewhat egg shaped is opened up by transverse pressure and it is sometimes easy to release the strap and leave the seal in condition to be resealed. This possibility is eliminated by the form of head in this present invention. As best shown in Fig. 6, the head is somewhat convex as a whole transversely—that is, the rear wall is curved or sunk inwardly and the front or opposite wall 16 is curved outwardly, consequently if the head is squeezed transversely the rear wall 18 is forced inwardly toward the opposite wall, and instead of freeing the end 10 to permit it to be withdrawn it actually locks the ends tighter in the head for the reason that the projection 19 is forced toward the opposite wall 16 of the head.

As many modifications of the invention will readily suggest themselves to one skilled in the art, I do not limit or confine the invention to the specific details of construction and operation herein shown and described.

I claim:

1. In a car seal, a strap of relatively thin sheet metal, a head having thicker walls, the head being closed and provided at one end with a slot of a size to admit only two thicknesses of the strap, the head being formed with top and bottom similarly transversely curved walls, one end of the strap fixed within the head and provided with a struck up projection extending toward the outwardly curved wall, the inwardly curved wall having

ing a formed up projection extending into the back of the struck up projection on the strap end, the other end of the strap having an opening adapted to receive the struck up projection of the secured end, the outwardly curved wall of the head being adapted to force the apertured end of the strap down over said formed up projection as said end is forced into the head.

10 2. In a car seal of the strap or ribbon type, a cap or head in which one end of the strap is irremovably fixed, the cap adapted to re-

ceive the other end of the strap, means for automatically latching said other end in the head, one side wall of the head being curved outwardly and convex in transverse cross-section and the opposite side wall concave and such curvatures extending substantially from edge to edge whereby transversely applied pressure will tend to close said walls together upon the strap ends.

In testimony whereof, I have hereunto set my hand, this 10th day of May, 1927.

JOHN KOROSCHETZ.
